UNITED STATES PATENT OFFICE.

WILLIAM F. STEUART, OF BLACKBANKS, ST. SIMON'S ISLAND, GEORGIA.

OYSTER-OPENER.

SPECIFICATION forming part of Letters Patent No. 402,867, dated May 7, 1889.

Application filed January 24, 1887. Serial No. 225,401. (No model.)

To all whom it may concern:

Be it known that I, WILLIAM F. STEUART, of Blackbanks, St. Simon's Island, Georgia, have invented a new and useful Machine for 5 Opening Oysters, of which the following is a specification.

This invention has for its objects to provide a machine for opening oysters which may be operated by foot-power, leaving the 10 hands of the operator free to manipulate the oysters, thus providing for rapidly opening the oysters, separating the same from the shells, and quickly disposing of the shells after the removal of the oysters, as more fully 15 hereinafter explained.

The above-mentioned objects I attain by the means illustrated in the accompanying drawing, in which is represented a perspective view of my improved machine.

20 Referring to the drawing, the letter C indicates a rectangular table having an opening in the top through which the shells are dropped as the oysters are opened, and B represents a chute inclining downward from a point below the opening to one end of the table, for the purpose of carrying the shells to a suitable place of deposit.

H represents a vertical curved knife, which is securely fastened to the table at one side 30 of the opening. To one of the side rails of the table are secured vertical standards E, between which is pivoted a pedal, E', extending to the front and rear of the table. To the rear end of said pedal is secured the lower 35 end of a vertical connecting-rod, A, the upper end of which is secured to the rear end of an oscillating lever, G, which is fulcrumed between vertical standards L, secured to the top of the table near the rear edge thereof.

40 The forward end of said lever extends directly over the knife H and partly over the opening in the top of the table, and is provided with a slot, h.

The letter D indicates a curved knife similar to the knife H, the said knife D being 45 provided with a screw-threaded shank, d,

which extends upward through the slot h in the lever G, and is adjustably confined therein by means of a thumb-nut, e, so that the position of the knife D may be adjusted with 50 reference to the knife H, as may be desired.

The operation of my invention will be readily understood from the above description, and is as follows: The operator stands at the front of the table opposite the knives 55 and the opening in the top of said table, holding the oyster in his hands, while he opens it by subjecting it to the action of the knives by means of the pedal. The oysters are removed from the shell as they are opened and 60 deposited in a suitable receptacle, while the shells are dropped through the opening and pass down through the chute out of the way.

Having described my invention and the operation thereof, what I claim, and desire to secure by Letters Patent, is—

1. The combination, with the table having an opening in the top and a chute below, of the stationary curved knife secured to the table, the oscillating lever carrying a curved 70 knife directly over the stationary knife, the connecting-rod, and the pedal connected to the lever by means of said rod, substantially as specified.

2. The combination, with the lower stationary knife, of the upper knife adjustably secured to an oscillating lever, whereby said upper knife may be adjusted with respect to the lower knife, substantially as and for the purpose set forth.

3. The combination, with the oscillating lever having a slot at its forward end, of the curved knife having a screw-threaded shank passing through the slot, and a thumb-nut whereby the knife may be adjusted with respect to the lower knife, substantially as shown and described.

WM. F. STEUART.
